UNITED STATES PATENT OFFICE.

DAVID F. BRUBAKER, OF GLEN CAMPBELL, PENNSYLVANIA.

MINER'S CAP.

1,081,659.

Specification of Letters Patent. Patented Dec. 16, 1913.

Application filed June 1, 1912. Serial No. 701,060.

To all whom it may concern:

Be it known that I, DAVID F. BRUBAKER, a citizen of the United States, residing at Glen Campbell, in the county of Indiana and State of Pennsylvania, have invented 5 a new and useful Miner's Cap, of which the following is a specification.

This invention relates to lamps for use by miners, drivers, motormen and others 10 employed under ground.

It has been found, that lamps such as commonly employed, will not remain upon the caps of the wearers when they strike overhanging timbers or other obstructions 15 and are often thrown to the ground and extinguished, thus leaving the user in darkness.

One of the objects of the present invention is to provide means whereby a lamp 20 will be held securely to the cap under the conditions stated, the holding means being simple and durable and necessitating no changes in the construction of the lamp proper.

25 A further object is to provide improved means for connecting the lamp to the crown of the cap, said means including guides for directing the lamp into proper position relative to one of the attaching elements.

30 With the foregoing and other objects in view which will appear as the description proceeds, the invention resides in the combination and arrangement of parts and in the details of construction hereinafter described and claimed, it being understood that changes in the precise embodiment of the invention herein disclosed can be made 35 within the scope of what is claimed, without departing from the spirit of the invention.

40 In the accompanying drawings the preferred form of the invention has been shown.

In said drawings:—Figure 1 is a perspective view of a cap with the present 45 improvements combined therewith. Fig. 2 is a vertical section through a portion of the cap and the parts attached thereto, the lamp being shown in elevation. Fig. 3 is a section on line A—B Fig. 2.

50 Referring to the figures by characters of reference C designates a cap having a vizor D. A supporting element designated generally at 1 is arranged upon the front portion of the cap and consists of a backing strip 2 of sheet 55 metal and a front strip 3 also of sheet metal, the two strips being of the same length and

being held together by means of the longitudinal edge portions of the plate 2 which are folded onto the plate 1 so as to form retaining flanges 4, as shown particularly 60 in Fig. 1. The supporting element has its upper portion bent back substantially at a right angle and riveted or otherwise secured upon the front portion of the crown of the cap C, this rearwardly extending portion 65 being indicated at 5. The lower portion of the supporting element is bent forwardly as indicated at 6 and is riveted or otherwise secured upon the vizor D.

A guide plate 7 is secured at its sides 70 upon the rearwardly extending portion 5 and is formed with parallel upstanding beads 8 forming a channel 9 therebetween, there being an opening 10 in the bottom of the channel adjacent the front end thereof. 75

A spring clip 11 is fastened, at its center, to the supporting element 1 at a point between the bent portions 5 and 6 and the arms of the clip converge forwardly and merge into outwardly rolled terminals 12. This 80 clip is of such size as to embrace and firmly clamp upon the body 13 of a torch lamp such as commonly employed, said body having a hooked stem 14 upon the rear portion thereof. Said stem has its pointed terminal ex- 85

tending downwardly and adapted to be seated within the opening 10. Said terminal is also adapted to extend into openings 15 formed within the strips 2 and 3 and registering with the opening 10. The opening 15 90 formed in the strip 2 is smaller than the other opening 15 so that, when the terminal of the stem is inserted into the openings, the pointed end of the stem will engage the walls of the lower opening 15 and thus be 95 supported so as to prevent the pointed end from sticking through the crown of the cap and possibly injuring the wearer. A reinforcing wire 16 is housed between the strips 2 and 3 close to the openings 15 and between 100 said openings and the front end of the rearwardly extending portion 5. This wire thus prevents the walls of the openings 10 and 15 from wearing forwardly too rapidly, and also serves to space the strips 2 and 3 apart 105 adjacent the opening 15, whereby the walls of said opening will engage the stem 14 at points considerable distances apart and will, consequently, prevent the stem from swinging within the openings. 110

When it is desired to fasten the lamp to the cap, the lower portion of the lamp body 13 is

forced between the outwardly rolled terminal portions of the clip 11 and said clip thus springs into engagement with the body of the lamp. The lamp can then be pushed 5 downwardly and during this movement the pointed terminal of the stem 14 will come into contact with one of the beads 8 and be deflected thereby and guided into the openings 10 and 15. The parts will thus assume 10 the positions illustrated in Figs. 1 and 2. As the clip 11 firmly engages the lamp at all times, it will be seen that, should the lamp strike an overhanging projection it will not become detached from the cap. In order to 15 detach the lamp it is first necessary to push it upwardly relative to the cap so as to withdraw the pointed end of stem 14 from the openings 10 and 15. The lamp must then be pulled forward with sufficient force to overcome 20 the resistance of the spring arms of clip 11. The intermediate portion of the supporting element 1 obviously serves to support the crown portion of the cap and to support the lamp from the visor D.

25 What is claimed is:—

The combination with a cap, of a supporting element including connected strips having rearwardly extending non-yielding portions arranged one above the other and secured 30 upon the crown portion of the cap, there being registering openings within said

portions, a combined spacing and reinforcing element interposed between the rearwardly extending portions of the strips and in front of the opening therein whereby said 35 openings are spaced apart, a spring clip extending forwardly from the supporting element, a lamp engaging the clip, a guide plate secured upon the upper rearwardly extending portion and having parallel corrugations forming beads with a channel therebetween, there being an opening in the bottom of the channel and registering with the other openings, said channel being extended longitudinally of the rearwardly extending portion on which the guide plate is mounted, and a stem having a downwardly extending pointed terminal portion bearing downwardly upon and engaging solely the wall of the lowermost one of the spaced 50 openings, that portion of the stem above the pointed terminal being held against swinging movement by the wall of the upper opening.

In testimony that I claim the foregoing as 55 my own, I have hereto affixed my signature in the presence of two witnesses.

DAVID F. BRUBAKER.
